CLAIM

The ornamental design for a waste receptacle, as shown and described.

DESCRIPTION

FIG. 1 is a top, front, left perspective view of a waste receptacle showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is another top view of the waste receptacle; and,

FIG. 8 is another top view of the waste receptacle.

The broken lines immediately adjacent to the shaded area represent unclaimed boundaries of the design. The other broken lines in the figures are to show portions of the waste receptacle and form no part of the claimed design.
